AMMONOLYSIS OF SECONDARY AND
TERTIAL AMINES

John F. Olin and Thomas E. Deger, Grosse Ile,
Mich., assignors to The Sharples Solvents Corporation,
Philadelphia, Pa., a corporation of Delaware

Application March 8, 1937, Serial No. 129,543

6 Claims. (Cl. 260—583)

The present invention pertains to the ammonolysis of derivatives of ammonia containing substituted or unsubstituted aliphatic or hydro-aromatic radicals as substituents for two or all of the hydrogen atoms of the ammonia molecule. It includes within its broad scope procedure by which such compounds containing between 1 and 20 carbon atoms in the aliphatic or hydro-aromatic radical attached to the nitrogen atom of ammonia may be reacted.

In the ammonolysis of halogen derivatives of aliphatic and hydro-aromatic compounds, the following reactions take place to a greater or less extent depending upon the ratio of reactants employed and other conditions:

- (1) $\text{NH}_3 + \text{RX} \rightarrow \text{RNH}_2 \text{X}$
- (2) $\text{RNH}_2 \text{X} + \text{RX} + \text{NH}_3 \rightarrow \text{R}_2\text{NH}_2\text{X} + \text{NH}_4\text{X}$
- (3) $\text{R}_2\text{NH}_2\text{X} + \text{RX} + \text{NH}_3 \rightarrow \text{R}_3\text{NHX} + \text{NH}_4\text{X}$

20 R representing the aliphatic or hydro-aromatic radical, X halogen, N nitrogen and H hydrogen.

It will be noted that three separate amino compounds are produced in accordance with the above reaction, the primary, secondary and tertiary aliphatic or hydro-aromatic derivatives of the ammonium halide, depending upon whether the reaction occurs in accordance with Equations 1, 2 or 3. When these three compounds are split by means of a base such as caustic soda, the following reactions occur:

- (4) $\text{RNH}_2\text{X} + \text{NaOH} \rightarrow \text{RNH}_2 + \text{NaX} + \text{H}_2\text{O}$
- (5) $\text{R}_2\text{NH}_2\text{X} + \text{NaOH} \rightarrow \text{R}_2\text{NH} + \text{NaX} + \text{H}_2\text{O}$
- (6) $\text{R}_3\text{NHX} + \text{NaOH} \rightarrow \text{R}_3\text{N} + \text{NaX} + \text{H}_2\text{O}$

35 It will be seen from the above equations that when a halogen derivative such as that discussed above is subjected to ammonolysis to produce simultaneously the primary, secondary and tertiary ammonium chloride derivatives of Equations 1, 2 and 3 and these ammonium chloride derivatives are split by means of a base such as caustic soda, a mixture of primary, secondary and tertiary amines is produced. The reactions represented by Equations (2) and (3) above, occur 40 particularly in connection with the ammonolysis of primary normal halides. The mono-alkyl amines formed by substitution of an amino radical for the halogen radicals of such compounds are in particular commercial demand. The object of 45 the present invention has been to develop a process by which, after separation of the primary amines from a mixture of amines obtained by the performance of Reactions 4, 5 and 6, the separated secondary and tertiary amines may be economically converted into primary amines or the

tertiary amines may be converted into secondary amines.

It is known that secondary and tertiary amines of the type indicated on the right hand side of Equations 4, 5 and 6 may be converted into primary amines in accordance with the following equations:

- (7) $\text{R}_2\text{NH} + \text{NH}_3 \rightarrow 2 \text{RNH}_2$
- (8) $\text{R}_3\text{N} + 2\text{NH}_3 \rightarrow 3 \text{RNH}_2$

10 It is also known that tertiary amines may be converted into corresponding secondary amines in accordance with the following equation:

- (9) $2\text{R}_3\text{N} + \text{NH}_3 \rightarrow 3 \text{R}_2\text{NH}$

15 The object of the present invention has been to effect reactions indicated in Equations 7, 8 and 9 in an efficient and economical manner on a large scale thereby producing primary amines by ammonolysis of secondary and tertiary amines, 20 and/or secondary amines by ammonolysis of tertiary amines.

25 The invention was developed in connection with research designed to convert secondary and tertiary amines containing aliphatic or hydro-aromatic hydrocarbon radicals having between 4 and 8 carbon atoms into primary and/or secondary amines.

30 The major part of the research upon which the invention was based was performed in connection with attempts to convert di- and tri-amyl amines into mono-amyl amines and/or di-amyl amines in accordance with Equations 7, 8 and 9. In connection with the treatment of secondary and tertiary amines in general to effect these results, the 35 principal feature of the invention consists in the discovery of a catalyst adapted to effect the above reactions in such a manner as to afford good yields of resultants at a high rate of conversion of reactants. In connection with the treatment of 40 secondary and tertiary amines having hydrocarbon radicals of between 4 and 6 carbon atoms, the invention includes the discovery of improved catalysts and reaction conditions for effecting the desired conversion with a minimum of degradation of the amino compounds treated into undesired products such as hydrocarbons, hydrogen, carbon and nitriles.

45 The invention will be best understood by reference to the attached flow sheet in which the 50 single figure represents a diagrammatic illustration of the continuous performance of the process of the invention.

55 Since the invention was conceived in connection with experiments involving conversion of di- and

tri-amyl amines into mono amyl amines, it will be described specifically with respect to such operations.

Referring to the drawing by reference characters, di- or tri-amyl amine or a mixture thereof is fed from a container 10 continuously into confluence with a stream of ammonia passed from container 11. The mixture of poly-amyl amines and ammonia is passed to a heater 13 in which it is heated to a temperature between 225° and 300° C., depending upon the pressure, space velocity, and the type of catalyst to be used in the ensuing ammonolysis reaction. The heated mixture is passed from the heater 13 to a reactor 14 filled with a catalytic mass.

The material of the catalytic mass constitutes the most important feature of the invention. The catalyst consists of activated carbon particles of 4 to 12 mesh size. While these carbon particles have sufficient catalytic effect to cause the desired reaction to take place in the reactor 14 at a fairly high velocity, they are preferably subjected to a special treatment designed to render them more effective. To this end, the carbon is stirred with a solution of the acetate or nitrate of the metal of which the oxide is ultimately to impregnate the carbon. The salt solution should be of approximately 20% concentration and should contain between 0.25 and 0.75 gram of salt in solution for every gram of carbon which is impregnated. After the carbon has been immersed in the salt solution for a period between 12 and 15 hours, the remaining salt solution is drained from the carbon and the wet carbon is heated to a temperature between 350 and 400° C. for a period of 2 to 3 hours in order to convert the salt into the corresponding oxide. The catalyst prepared in this manner is then placed in the reactor 14 as stated above.

The reactor is maintained at a temperature of 240 to 325° C. depending upon the nature of the amine being subjected to ammonolysis, the nature of the catalyst and the space velocity. In this connection it is to be noted that butyl amines should be subjected to temperatures in the heaters 13 and 14 which are approximately 25° higher than those employed in the corresponding treatment of amyl amines, for a given space velocity and pressure. Hexyl and cyclohexyl amines should be subjected to temperatures approximately 25 degrees lower than those employed in converting amyl amines under similar conditions. Material passed through the reactor 14 is condensed in condenser 15 and passed thence to a container 16.

The best impregnating material for supplementing the catalytic effect of the activated carbon used as a catalyst in the practice of the process is manganese oxide and the preparation of this catalyst involves impregnating the carbon with manganese nitrate as described above. The oxides of aluminum, cerium, thorium, silicon, chromium, zinc or iron may be used in place of the manganese oxide as a promoting material for the carbon but these oxides have not been found to be as desirable as manganese oxide, in that they produce greater quantities of by-products on the one hand or are less active on the other.

The pressure under which the ammonia and amines are passed confluently through the series of steps discussed above may be varied within wide limits within the practice of the invention. It is only necessary that sufficient pressure be employed to cause the desired flow of these reactants through the apparatus and the pressure

may therefore vary between 10 mm. absolute and 1000 pounds per square inch gauge pressure. Excellent results have been obtained in connection with pressures of about 300 pounds per square inch.

Care should be taken to avoid temperatures which are substantially higher than those discussed above in connection with the operation of the reactor 14, for much higher temperatures will result in a substantial amount of undesired pyrolysis of the materials under treatment in cases in which secondary and tertiary amines containing hydrocarbon radicals having between 4 and 6 carbon atoms are treated. The lower limits of the temperatures necessary to effect fairly rapid conversion of the amines are substantially the lower limits indicated with respect to the reactor 14 and the upper limits are substantially the limits necessary to avoid undesired pyrolysis but these limits will vary somewhat depending upon the particular metal oxide with which the carbon is impregnated, pressure and other factors. As a general rule, it may be stated that the oxides which have the maximum beneficial effect in promoting the desired reaction also have a maximum effect in promoting pyrolysis.

The velocity of flow of materials through the process may vary within fairly wide limits, as may also the ratio of ammonia to secondary and/or tertiary amines. In the treatment of di-amyl amine to produce mono-amyl amine, excellent results have been obtained by passing a molecular excess of ammonia through the apparatus bearing a ratio of between 5 and 15:1 to the di-amyl amine under treatment. Best results have been attained when these materials are passed through the apparatus at a velocity of between 200 and 2000 liters of gaseous mixture per hour per liter of catalyst, the volume of gaseous mixture being computed on the assumption that the mixture is under standard conditions of zero degrees C. and 760 mm. pressure (space velocity of 200-2000).

Optimum results have been attained in conversion of poly-amyl and -butyl amines into corresponding mono-amines when temperatures of 240-325° C. are used in connection with a space velocity of 500-1000. If the space velocity is substantially lowered the operating temperature may be lowered; and if the space velocity is increased, a more elevated temperature will be necessary. To show the magnitude of such effect, it is estimated that at a space velocity of 10 one might use a temperature as low as 180° C. with good results; while at a space velocity of 35,000 a temperature of 400° C. might be necessary for good conversion.

Pressure will also play an important part in reaction velocity, since the greater the pressure, the greater will be the concentration of reactants in contact with the catalyst. Thus at 150 pounds per square inch, ten times as much gas will be in contact with the catalyst as at atmospheric pressure. Thus, increase in pressure, like decrease in space velocity, makes possible the use of lower temperatures.

EXAMPLE I

Monoamylamine from diamylamine

Diamylamine in container 10 and ammonia in container 11 were pumped in a mol ratio of 8.7 ammonia : 1 diamylamine and mixed before entering preheater 13, where the liquid mixture was completely volatilized and entered the bot-

tom of reactor 14 containing 8 liters of a catalyst, in this case activated carbon impregnated with manganese oxide. The temperature of the reactor was 237° C. and pressure was 300 lbs./sq. in. The space velocity of the gases passing through the reactor was 601 liters gas per liter of catalyst per hour. At the end of 3.32 hours 25.4 lbs. of diamylamine and 23.9 lbs. of ammonia had been passed through the reactor. The gases leaving the top of reactor 14 were condensed in condenser 15 and collected in receiver 16. The ammonia was distilled off from the recovered liquid under approximately 250 lbs. pressure and the residue cooled to room temperature. The residue was removed from the bottom of the still and fractionated through an efficient column.

The following fractions were obtained:

20	To 90° C.	799 g.	88.9% monoamylamine
90-97	3649 g.	100. % monoamylamine	
97-130	155 g.	83.1% monoamylamine	
130-188	3724 g.	94.3% diamylamine	
188-230	1521 g.	95.4% diamylamine	
230-270	819 g.	98.7% triamylamine	
25	Residue	628 g.	

The conversion to monoamylamine in this run was 35.9% and the yield of monoamylamine 74.5%.

EXAMPLE II

The same method was used as in Example I. The diamylamine and ammonia were pumped into the preheater at a mol ratio of 11.31 ammonia : 1 diamylamine. 6.9 liters of catalyst, which in this case was activated carbon impregnated with cobalt oxide was retained in the reactor. The temperature was 236° C. and pressure was 300 lbs. At the end of 3.55 hours, 23.8 lbs. diamylamine and 29.19 lbs. ammonia had been pumped through at a space velocity of 774 liters gas per liter catalyst, per hour. After the ammonia was distilled off from the liquid, the residue was fractionated and the following cuts were made.

45	To 95° C.	154 g.	92.3% monoamylamine
95-105	2761 g.	98.3% monoamylamine	
105-124	87 g.	68.0% monoamylamine	
124-220	2921 g.	85.2% diamylamine	
50	Residue	2113 g.	98.0% triamylamine

The conversion to monoamylamine in this run was 37.0% and yield of monoamylamine was 68.9%.

EXAMPLE III

55 A 9.34:1 mol ratio of ammonia to diamylamine was preheated and passed through a reactor at atmospheric pressure and 325° C. The reactor contained 2.0 liters activated carbon impregnated with manganese oxide. The gases were passed through at a space velocity of 1080 liters gas per liter catalyst per hour. The ammonia was removed from the recovered liquid and the residue fractionated. The usual cuts were made and a 33.6% conversion and 90% yield of monoamylamine was obtained.

EXAMPLE IV

Monobutylamine from dibutylamine

70 The dibutylamine and ammonia at a mol ratio of 10.05 ammonia:1 dibutylamine were pumped through the preheater and the reactor at a temperature of 293° C. and pressure of 300 lbs./sq. in. The reactor contained 7.0 liters of activated carbon impregnated with manganese ox-

ide. The space velocity was 863 liters gas per liter catalyst per hour. At the end of 3.7 hours, 25.7 lbs. dibutylamine and 34.0 lbs. ammonia were added. The ammonia was distilled from the recovered liquid and the residue was fractionated into the following cuts:

To 82° C.	3728 g.	95.2% monobutylamine
82-120	517 g.	54.2% monobutylamine
120-140	27 g.	66.8% dibutylamine
140-170	4911 g.	99.0% dibutylamine
170-200	63 g.	82.5% dibutylamine
200-225	1485 g.	97.4% tributylamine
Residue	878 g.	

The conversion to monobutylamine was 31.4% and the yield of monobutylamine was 77.6%.

EXAMPLE V

Monobutylamine from tributylamine

The tributylamine and ammonia at a mol ratio of 13.56 ammonia:1 tributylamine were pumped through a preheater and reactor held at 375° C. and 300 lbs. per sq. in. pressure. The reactor contained 8.0 liters activated carbon impregnated with manganese oxide. The gases were passed through the reactor at a space velocity of 644 liters gas per liter of catalyst per hour. At the end of 3.92 hours 25.22 lbs. tributylamine and 31.42 lbs. ammonia had passed through the apparatus. The ammonia was removed by pressure distillation from the recovered liquid. The residue was fractionated into the following cuts:

To 70° C	25 g.	90.6% monobutylamine
70-79	3883 g.	91.4% monobutylamine
79-82	669 g.	87.9% monobutylamine
82-118	855 g.	21.8% monobutylamine
118-140	186 g.	43.5% dibutylamine
140-170	2388 g.	96.2% dibutylamine
170-195	86 g.	70.3% dibutylamine
195-220	626 g.	97.0% tributylamine
Residue	2267 g.	

The conversion to monobutylamine was 32.0%. The yield of monobutylamine was 43.0%.

Modifications will be obvious to those skilled in the art and we do not therefore wish to be limited except by the scope of the subjoined claims.

We claim:

1. The process of converting amines chosen from the group consisting of secondary and tertiary alkyl amines containing between 1 and 8 carbon atoms in their alkyl radicals, and secondary and tertiary cyclohexyl amines, into the corresponding primary and secondary amines, which comprises reacting said secondary and tertiary amines with ammonia by passing said amines together with ammonia over a catalyst consisting of activated carbon impregnated with manganese oxide.

2. The process of converting amines chosen from the group consisting of secondary and tertiary alkyl amines containing between 1 and 8 carbon atoms in their alkyl radicals, and secondary and tertiary cyclohexyl amines, into the corresponding primary and secondary amines, which comprises reacting said secondary and tertiary amines with ammonia by passing said amines together with a molecular excess of ammonia over a catalyst consisting of activated carbon impregnated with manganese oxide.

3. The process of converting amines chosen from the group consisting of secondary and tertiary alkyl amines containing between 1 and 8

- carbon atoms in their alkyl radicals, and secondary and tertiary cyclohexyl amines, into the corresponding primary and secondary amines which comprises reacting said secondary and tertiary amines with ammonia by passing said amines together with ammonia at a temperature between 240° C. and 400° C. over a catalyst consisting of activated carbon impregnated with manganese oxide.
10. 4. The process of converting amines chosen from the group consisting of secondary and tertiary alkyl amines containing between 1 and 8 carbon atoms in their alkyl radicals, and secondary and tertiary cyclohexyl amines, into the corresponding primary and secondary amines which comprises reacting said secondary and tertiary amines with ammonia by passing said amines together with ammonia at a temperature between 240 and 325° C. over a catalyst consisting of activated carbon impregnated with manganese oxide.
15. 5. The process of converting amines chosen from the group consisting of secondary and ter-

tiary alkyl amines containing between 4 and 6 carbon atoms in their alkyl radicals, and secondary and tertiary cyclohexyl amines, into the corresponding primary and secondary amines, which comprises reacting said secondary and tertiary amines with ammonia by passing said amines together with ammonia over a catalyst consisting of activated carbon impregnated with manganese oxide.

6. The process of converting amines chosen from the group consisting of secondary and tertiary alkyl amines containing between 4 and 8 carbon atoms in their alkyl radicals, and secondary and tertiary cyclohexyl amines, into the corresponding primary and secondary amines, which comprises reacting said secondary and tertiary amines with ammonia at a temperature between 240 and 325° C. over a catalyst consisting of activated carbon impregnated with manganese oxide.
